UNITED STATES PATENT OFFICE.

MILTON H. HART, OF NEW YORK, N. Y.

FIRE-HOSE NOZZLE.

SPECIFICATION forming part of Letters Patent No. 597,182, dated January 11, 1898.

Application filed October 16, 1896. Serial No. 609,122. (No model.)

To all whom it may concern:

Be it known that I, MILTON H. HART, of New York, in the county and State of New York, have invented certain new and useful 5 Improvements in Nozzles for Fire-Hose, of which the following is a specification.

My invention relates to a compound or combination nozzle, so as to have either a straight stream or a spray-stream or what is called a 10 "chemical" straight stream of small diameter. When one of these is in use the other is shut off.

I have shown in the drawing a longitudinal section of my nozzle.

15 *a* represents the nozzle provided for the full-size straight stream, having its orifice at *a'*.

b is a nozzle provided with the two waterways *c* and *d*.

20 *c* is a waterway or pipe for a spray-stream, having a head with orifices *j* of different degrees of pitch—that is, placed at different angles to the axis of the nozzle *c*.

25 *d* is a waterway or pipe for conveying the small-sized straight stream. This waterway runs through the waterway or tube *b* without communicating or connecting with it and has an orifice or head independent of that provided for the pipe *b*.

e (shown in dotted lines) is a lever for turning the valve *k*, so as to open either of the 30 two waterways *a* or *c* and close the other, *k'* being the closing portion of the valve, by which the waterway *a* or *c* is opened or closed, as may be desired.

h is a valve for opening the tube *d*, provided with the lever *i* and the stop *f*, which impinges against the stud *g*. 35

It will be seen that by the use of my improved nozzle either one of the three streams referred to may be used at pleasure and the 40 others shut off.

What I claim, and desire to secure by Letters Patent, is—

The improved combination-nozzle, consisting of the waterway *a*, for a straight stream; 45 the waterway *c*, for a spray-stream; the waterway *d*, for a small-sized straight stream; the valve *k*, provided with the lever *i*; and the valve *h* and lever *i*; in combination, substantially as and for the purpose above described. 50

MILTON H. HART.
